UNITED STATES PATENT OFFICE

137,846

DESIGN FOR A COLLAR STAY

Ben B. Manaster, Chicago, Ill., assignor of one-half to Charles I. Greener, Chicago, Ill.

Application February 26, 1944, Serial No. 112,728

Term of patent 14 years

(Cl. D17—8)

To all whom it may concern:

Be it known that I, Ben B. Manaster, a citizen of the United States and a resident of Chicago, in the county of Cook and State of Illinois, have invented a new, original, and ornamental Design for a Collar Stay, of which the following is a specification, reference being had to the accompanying drawing, forming a part thereof, and in which:

Fig. 1 is a front elevational view of a collar stay showing my new design; and

Fig. 2 is a side view of the same.

I claim:

The ornamental design for a collar stay, as shown.

BEN B. MANASTER.
